UNITED STATES PATENT OFFICE.

CARL SCHWINTZER AND WILHELM GRÄFF, OF BERLIN, GERMANY, ASSIGNORS
OF ONE-HALF TO J. F. DONNELL & CO., OF NEW YORK.

LAMP-BURNER.

SPECIFICATION forming part of Letters Patent No. 289,571, dated December 4, 1883.

Application filed July 28, 1883. (No model.) Patented in Germany November 14, 1879, No. 10,621, January 13, 1880, No. 10,846, and March 26, 1880, No. 11,713.

To all whom it may concern:

Be it known that we, CARL SCHWINTZER and WILHELM GRÄFF, subjects of the King of Prussia, German Emperor, residing at the city 5 of Berlin, Prussia, Germany, have invented certain new and useful Improvements in Lamp-Burners, (for which Letters Patent have heretofore been granted to us by the government of Germany, No. 10,621, dated November 14, 10 1879, No. 10,846, dated January 13, 1880, and No. 11,713, dated March 26, 1880,) of which the following is a specification.

This invention has reference to an improved lamp-burner of that class in which a series of 15 wick-tubes are arranged equidistantly from the axis of the burner, and moved up and down in a series of guide-tubes, the burners of said class being known by the name of "mitrailleur" burners; and the invention consists of 20 a ring-shaped cap arranged at the upper part of fixed guide-tubes, said cap being provided with openings for the wicks. The pinion by which the wicks and wick-tubes are adjusted is placed entirely within an annular casing of 25 the burner, and is rendered accessible by a detachable ring at the lower part of said casing. The actuating-pinion engages a rack-bar that is attached by an inwardly-extending arm to the center of the bottom plate of the wick- 30 tubes, said rack being located between two adjoining wick-tubes. The bottom plate of the wick-tubes is provided with a hinged stop device, so as to prevent the wick-tubes from projecting above the guide-tubes and thereby 35 avoid the burning of hooks arranged at the upper ends of the wick-tubes.

In the accompanying drawings, Figure 1 represents a side elevation of my improved burner. Fig. 2 is a vertical central section of 40 the same; and Figs. 3, 4, 5, and 6 are horizontal sections, respectively, on lines *v v*, Fig. 1, and *x x*, *y y*, and *z z*, Fig. 2.

Similar letters of reference indicate the corresponding parts.

In the drawings, *A* represents an annular casing which encircles a series of fixed guide-tubes, *a a*, that are arranged equidistantly from the axis of the burner. To the upper ends of the guide-tubes *a a* is attached a ring-shaped

cap, *a'*, which is provided with openings for 50 the wick and wick-tubes *b b*. The ring-shaped cap *a'* closes the intermediate space between the upper ends of the tubes *a a*, so as to protect not only the upper ends of the guide-tubes against being burned by the flame, but 55 also produces a continuous and even flame, which would not be the case if direct access of air be given to each wick. The inner flange of the ring-shaped cap *a'* is much shorter than the outer flange, so that the air that is 60 drawn through the interior of the burner and fed to the inner surface of the flame is obstructed as little as possible, while the larger outer flange conducts the air to the outer surface of the flame. At its lower part the casing *A* is furnished with a detachable ring, *A'*, that is screwed over the threaded portion of 65 said casing. The threaded portion serves, also, for the purpose of screwing the burner into the collar of the neck of the oil-receptacle. 70

On a shoulder of the casing *A* a gallery of the usual construction is supported, by which air is conducted to the wicks and a support is furnished for the chimney. At the inside of the casing *A* are arranged bearings *b'* for a pinion-shaft, *b²*, which is extended laterally through an opening of the casing, and provided at the outer end with the usual milled head. A pinion, *C*, is fastened to the shaft *b²* intermediate between the bearings *b'*, and is entirely inclosed by the casing *A*, but readily accessible for repairs by means of the detachable screw-ring *A'*. The pinion *b* engages a vertical rack, *C'*, which is located between two adjoining wick-tubes, *a a*, and provided with 80 an inwardly-bent arm that is attached to the center of the bottom plate, *D*, of the wick-tubes. By thus securing the inwardly-extending arm of the rack *C'* to the center of the bottom plate, the easy and regular up-and-down motion of the wick-tubes is secured, while side strains that might interfere with the easy motion of the wick-tubes in the guide-tubes are obviated. The wick-tubes *b b* are moved up and down in the guide-tubes *a a* by the action 85 of the rack and pinion, the motion of the rack *C'* being steadied by openings in the top and bottom plates of the casing *A*. To the bottom 90

plate, D, of the wick-tubes is applied a hinged stop device, E, which can be thrown in vertical or horizontal position, as shown in Fig. 2. When in vertical position, the stop E abuts 5 against the bottom plate of the casing A when the wick-tubes are raised to that extent, and prevents thereby the upper ends of the 10 wick-tubes from projecting above the upper ends of the guide-tubes, thereby avoiding the 15 burning of the wick-holding hooks at the upper ends of the wick-tubes. In this position the stop E is retained by means of its hook-shaped upper part, which is pressed between two adjoining wick-tubes, as shown in Fig. 1, and thereby retained in position. When wicks 20 d^2 are to be inserted into the wick-tubes b , the stop device E is placed in a horizontal position, as shown in dotted lines in Fig. 2. The pinion C is then turned and the wick-tubes b 25 b raised until their upper ends are caused to project above the guide-tubes a , so that the wicks can be readily drawn in by a suitable device for this purpose.

The advantages of our improvements are that 25 they give a continuous flame, that they obviate the necessity of providing a special casing for the pinion, and also furnish ready access to the latter. The rack is preserved from injury by being placed between two of the wick-tubes, 30 while the stop device prevents injury to the hooks at the upper ends of the wick-tubes, which would render the burner useless.

Having thus described our invention, we 35 claim as new and desire to secure by Letters Patent—

1. In a lamp-burner of the class described, the combination, with the guide-tubes, of a ring-shaped cap provided with openings for the wicks, said cap being applied to the upper ends of the guide-tubes so as to close the intermediate spaces between the same, substantially as set forth. 40

2. In a lamp-burner of the class described, the combination of the fixed guide-tubes, a series of wick-tubes moving therein, a rack for 45 actuating the same, arranged at one side thereof, a pinion for engaging the rack, and an annular inclosing-casing made of a fixed portion and a detachable ring-section, whereby ready access is given to the pinion, substantially as 50 set forth.

3. In a lamp-burner of the class described, the combination of a system of wick-tubes connected by a bottom plate, a series of guide-tubes, means for raising or lowering the wick-tubes, and a stop device hinged to the bottom plate and adapted to be thrown into vertical or horizontal position, so as to serve either as a stop for the wick-tubes or admit their being raised above the guide-tubes for inserting the 55 wicks, substantially as specified.

In testimony that we claim this as our own invention we have hereunto set our hands in the presence of two subscribing witnesses.

CARL SCHWINTZER.
WILHELM GRÄFF.
